HOOD CATCH AND BRACKET THEREFOR

Frank P. Sargent, Detroit, Mich., assignor to The Bassick Company, Bridgeport, Conn., a corporation of Connecticut

Application March 7, 1936, Serial No. 67,616

3 Claims. (Cl. 292—340)

The present invention relates to an improved hood catch and bracket therefor, and has for an object to provide a hood catch in which the manually operable means for engaging and disengaging the catch means is mounted upon a fixed part of the automobile structure and in which the keeper brackets with which the catch means cooperate are mounted upon the hood, thereby providing a structure of simple construction, in which 5 the movable operating parts of the catch are at all times protected and concealed, and which, because of their mounting upon a fixed structure may be most conveniently and positively operated. It is particularly proposed to provide a 10 catch in which the operating handle is disposed at a fixed central point and operates catch means which cooperate with keeper brackets at the ends of the hood. A further object is to provide a hood catch which when released will cause the hood 15 to be automatically raised so that it can be conveniently engaged by the fingers and lifted to open position, thereby dispensing with the lift handle usually provided upon the sides of the hood.

With the above and other objects in view an embodiment of the invention is shown in the accompanying drawing, and this embodiment will be hereinafter more fully described with reference thereto, and the invention will be finally 20 pointed out in the claims.

In the drawing:

Fig. 1 is a side elevation of an automobile hood provided with hood catch and bracket means according to the invention.

Fig. 2 is an enlarged vertical sectional view, taken along the line 2—2 of Fig. 1.

Fig. 3 is an inside elevation of the parts as shown in Fig. 2, with portions of the supporting structure and hood broken away.

Fig. 4 is a plan view of the keeper bracket as shown in Fig. 2, the hood being partially broken away.

Fig. 5 is a vertical sectional view of the parts as shown in Fig. 2, and showing the catch released 45 and supporting the hood in partially raised position.

Fig. 6 is a longitudinal sectional view of a hood, of the type which is hinged at its rearward edge to the frame, provided with hood catch and bracket means according to the invention.

Similar reference characters indicate corresponding parts throughout the several figures of the drawing.

Referring to the drawing the engine compartment of the automobile is surrounded by a fixed

wall structure 10 having an opening 11 which is normally closed by the hood comprising a pair of hood sides 12 hingedly mounted over the opening 11 by means of a hinge connection 13. The end edges of the hood sides are arranged to overlap the ends of the opening 11 and will preferably engage the usual lacings along the edge of the opening, and the lower edges of the hood sides overlap the lower edges of the opening and in the closed position are pressed inwardly against the 10 fixed walls 10.

The hood catch illustrated is of a type known as a center handle catch, and heretofore has been mounted upon the hood side to cooperate with brackets mounted upon fixed parts of the automobile frame. In the present invention the catch is mounted upon the fixed part 10 and cooperates with brackets upon the hood. The catch is the same at each side of the hood so that only one will be described in detail. The catch comprises a 15 rock shaft 14 which extends longitudinally along the interior of the side wall 10 and is journaled near its ends in bearing brackets 15—15 secured to the wall 10 and is also journaled adjacent its center in bearing bracket 16—16 bent from the 20 upper edge of a mounting plate 17 which is secured to the inner side of the wall 10, as by spot-welding or other suitable means.

Between the bearing brackets 16—16 the rock shaft is angularly bent to substantially V-form to 25 provide a crank portion 18, which is engaged by an eye 19 at the upper end a connecting rod 20, the lower end of this connecting rod being bent at a right angle, as at 21, and pivotally engaged in an aperture 22 in the end of a crank arm 23 mounted 30 upon the inner end of the operating handle 24, the shank of this handle being journaled in the mounting plate 17 and extended through a suitable aperture in the side wall 10. The outer ends of the rock shaft 14 are bent outwardly and longitudinally to provide offset crank ends 25—25 disposed parallel to the rock shaft, the offset of these crank ends being relatively greater than that of the crank portion 18 and also being angularly offset with respect to said portion 18. These crank 35 ends are adapted to engage the keeper brackets presently to be more fully described, and in the engaged position produce a torsion twist and tension in the rod 14, which for this purpose is formed of suitable spring metal, the tension thus 40 set up exerting an upward pull on the connecting rod 20 and the crank arm 23 to retain the latter in the locking position at one side of the dead center, as clearly shown in Fig. 3.

The keeper brackets are of similar construction 55

and are provided at the ends of both of the hood sides 12 in positions to cooperate with the crank ends 25 of the hood catches at each side of the hood, the front and rear keeper brackets, however, being reversed with respect to each other but otherwise of identical construction. For convenience, therefore, only one of the brackets will be described in detail, this being the rear left bracket illustrated in detail in Figs. 2 to 5. This keeper bracket comprises an arcuate mounting flange portion 26, shaped to conform to the curvature of the hood side, and which is secured to its interior surface upwardly spaced relation to the lower edge of the hood side by spot-welding, as at 27, or by any other suitable means. A side plate portion 28 from which the flange 26 is bent projects inwardly and downwardly and at its inner end is provided with a right angularly bent vertically disposed flange 29 provided at its lower end with a forwardly and downwardly inclined keeper lip portion 30, with which the crank end 25 is adapted to engage in the locked position of the catch. The side portion 28 is preferably embossed with a reinforcing rib 31 to stiffen it. The lower edge of the side portion 28 comprises a vertically extending forward edge portion 32 spaced inwardly from the inner surface of the lower marginal edge portion of the hood side to provide a recess within which the upper edge of the fixed wall portion 10 engages in the closed position of the hood, a horizontal edge portion 33 extending inwardly from the lower end of the edge portion 32, and a curved cam edge portion 34 in continuation of the horizontal edge portion 33 and curved inwardly and downwardly to the inner end of the lip portion 30. The edge portions 34 and 33 constitute cam means for engagement by the crank end 25 when the hood catch is released for causing the hood side to be partially raised so that its lower edge may be conveniently gripped by the fingers for the purpose of completely raising the hood side.

The operation is as follows:

In order to release the hood the operating handle 24 which is normally in a horizontal position is raised through a quarter turn to vertical position, first causing the crank lever 23 to be forced over the dead center from its locked position, whereupon the rock shaft is rotated to the position shown in Fig. 5 the crank end 25 first riding upon the curved surface 34 and then into engagement with the horizontal edge surface 33 and raising the hood so that its lower edge is in upwardly spaced relation to the upper edge of the wall portion 10. The hood side may thereupon be conveniently gripped by the fingers and moved to its fully raised position. In order to close the hood it is only necessary to engage the crank ends 25 above the lip portions 30 of the keeper brackets and swing the handle 24 to its locked position, the crank ends being pressed downwardly upon the lip portions which through their in-

clination cause the hood to be pulled downwardly and inwardly and firmly retained in closed position through the tension set up in the rock shaft 14.

In Fig. 6 I have illustrated the catch and bracket means provided in a hood structure in which the hood 12 is hinged at its rearward edge, as at 13, to the automobile frame structure. The actuating handle 24 of the catch is preferably mounted centrally of the forward fixed 10 wall 10a and the brackets are mounted interiorly of the hood adjacent the ends of its forward portion. The operation is substantially similar to that of the first embodiment, the hood being partially lifted upon release of the catch by engagement of the crank ends 25 with the cam surfaces 34 and 33 of the brackets.

I have illustrated and described a preferred and satisfactory embodiment of my invention, but it will be obvious that changes may be made 20 therein, within the spirit and scope thereof as defined in the appended claims.

Having thus described my invention what I claim and desire to secure by Letters Patent is:—

1. For use in an automobile hood structure 25 comprising a side wall, a hinged hood section, and manually operable catch means mounted interiorly of said side wall, a keeper bracket adapted to be secured upon the interior of said hood section to be engaged by said catch means to secure the hood section in closed position, and cam means on said bracket adapted to be engaged by said catch means upon releasing movement to raise the hood section upwardly relatively to said wall.

2. For use in an automobile hood structure comprising a side wall, a hinged hood section, and manually operable catch means mounted interiorly of said side walls, a keeper bracket secured upon the interior of said hood section having a downwardly and outwardly inclined portion adapted to be engaged at its upper side by said catch means upon downward movement of said catch means to secure the hood section in closed position and a cam portion adapted to be engaged by said catch means upon upward releasing movement to raise the hood section upwardly relatively to said side wall.

3. A hood catch keeper bracket, adapted to be secured to a hood section in relation to be engaged by catch means having downward securing movement and upward releasing movement, comprising a keeper portion adapted to be engaged at its upper side by said catch means upon downward securing movement to secure the hood section in closed position and a cam portion adapted to be engaged by said catch means upon upward releasing movement to raise the hood section upwardly.

FRANK P. SARGENT. 60
